UNITED STATES PATENT OFFICE.

ANTON KULICH, OF BROOKLYN, NEW YORK.

BED-LOUNGE.

SPECIFICATION forming part of Letters Patent No. 328,894, dated October 20, 1885.

Application filed April 4, 1885. Serial No. 161,171. (No model.)

To all whom it may concern:

Be it known that I, ANTON KULICH, of Brooklyn, in the county of Kings and State of New York, have invented certain new and 5 useful Improvements in Bed-Lounges, of which the following is a specification.

In the accompanying drawings, Figure 1 represents a front elevation of my improved bed-lounge before upholstering. Fig. 2 is a 10 plan of the same with parts broken away, and Figs. 3 and 4 are vertical transverse sections of the bed-lounge respectively in a position as a lounge and as a bed.

Similar letters of reference indicate corresponding parts.

Referring to the drawings, A represents the main frame of my improved bed-lounge, which is provided with a fixed back, B.

To the front part of the main frame A are 20 attached forward-extending metallic brackets C. A seat-section, D, is pivoted to these brackets C by means of metallic straps C', which are firmly secured to the ends of said seat-section by bolts or in any other suitable 25 manner. A second movable seat-section, E, carries metallic straps e', and said seat-section D has similar straps, e', said straps running back for some distance from the meeting edges of the seat-sections, and being firmly secured 30 thereto by bolts or in any other suitable manner, and the outer or meeting ends of said straps being bifurcated or forked. Pivot-links e e connect said seat-sections, being pivoted in the bifurcated ends of said straps.

To the rear part of the frame of the movable section E are hinged short legs E', which are folded closely to the under side of the section E when the sections D and E are folded one over the other in forming a lounge, 40 but which are dropped into vertical position so as to rest upon transverse stays F of the main frame when the seat-section is swung on the supporting-brackets C C in forward position, as shown Fig. 4. The seat-section D is 45 connected with the hinged legs E' by stout strings f, which are stretched when the seat-section is folded over the movable section E, as shown in Fig. 3, so as to move up the legs E' and fold them away below the section E, 50 which gives sufficient play to the downward swinging of the legs E' when the seat-section

D is opened. The outer end of the seat-section D is provided with the customary legs, D', which are pivoted to the frame of the section and adapted to be folded away alongside 55 of the same when the seat-section D is folded over the section E, as shown in Fig. 3, but which drop into vertical position, so as to support the seat-section when in extended position, as shown in Fig. 4.

By pivoting the seat-section D to raised brackets C C, and connecting it by pivot-links and straps to the inner movable section E, the latter is lifted by the outwardly-swinging motion of the seat-section D, so as to assume a position on a level with the seat-section, and at nearly the same level which the same assumes when folded over the inner section, E. By the inwardly-swinging motion of the seat-section D the section E is lowered 70 into the main frame below the seat-section, which latter is then at a position having the normal height of seat-sections in bed-lounges.

The head of the lounge is made of a fixed section, G, and a hinged section, G', which is 75 swung in outward direction, and supported on the seat-section by a stop-plate, g, as customary in bed-lounges. By this construction the bed-lounge can be changed into a bed having nearly the same height as common beds, 80 whereby the same is more convenient for use, while it can be handled with the same facility as the common bed-lounges in which the seat-section is hinged to the main frame.

I am aware that bed-lounges with one or 85 more movable seat-sections hinged to each other and to the frame-work of the lounge are old; and also that there is nothing new in the folding legs or means for actuating them herein described; and I do not, therefore, lay any claim to such features, my invention consisting in the specific means of pivoting one seat-section to the frame, and the other seat-section thereto, substantially as described.

Having thus described my invention, I claim as new and desire to secure by Letters Patent—

In a bed-lounge, a main frame provided with supporting-brackets at its ends, a movable seat-section, metallic straps secured to the ends thereof and pivoted to said brackets, a second movable seat-section, oppositely

disposed metallic straps secured to both said seat-sections, the meeting ends thereof being bifurcated, connecting pivot-links pivoted in said bifurcated ends, and hinged legs for supporting the seat-sections, substantially as set forth.

In testimony that I claim the foregoing as

my invention I have signed my name in presence of two subscribing witnesses.

ANTON KULICH.
